COIN DISPENSING MACHINE

Roy J. Labbe, Baltimore, Md.

Application January 15, 1951, Serial No. 206,110

2 Claims. (Cl. 133—5)

1

This invention relates to a coin dispensing machine, and more particularly to a machine which automatically stacks coins of a given denomination, after which the coins may be removed from the machine in measured quantities.

Briefly, the invention includes a hopper, the bottom of which is formed with a rotating disc having a series of openings adjacent the periphery, the diameter of the openings being slightly larger than the diameter of the coins being dispensed. A bed plate is positioned beneath the rotating disc which, with the walls of the openings, form pockets into which the coins fall as the disc rotates. The bed plate is provided with an opening, in the vicinity of its periphery, through which the coins fall as the openings in the disc pass thereover when the disc is rotated. A tube is positioned beneath the bed plate in register with the opening therein, and the coins passing thru the opening in the bed plate drop into this tube. Dispensing mechanism is provided at the lower end of the tube so that coins may be removed from the tube in measured quantities. Control mechanism is also associated with the tube for automatically filling the tube whenever coins are dispensed.

An object of my invention is to provide an improved coin dispensing machine.

Another object of my invention is to provide an improved machine for automatically stacking coins of like denomination.

Yet another object of my invention is to provide an improved machine for stacking and dispensing coins of the same denomination, wherein the coins may be removed from the machine in measured quantities.

Still another object of my invention is to provide a coin dispensing machine having improved control means associated therewith, whereby the supply of stacked coins is automatically replenished, if coins are available for stacking, whenever a measured quantity of coins is dispensed.

A further object of my invention is to provide an improved coin stacking and dispensing machine which may be easily and quickly operated by the user to efficiently and accurately dispense coins.

Yet a further object of my invention is to provide a coin stacking and dispensing machine which is strong and sturdy in construction, consisting of relatively few parts, and not liable to get out of order even after long and continuous use.

With these and other objects in view, which may be incident to my improvements, the inven-

2

tion consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the accompanying drawings, in which is shown one of the various possible embodiments of this invention:

Figure 1 is a perspective view of the machine.

Fig. 2 is a vertical sectional view taken on line

20 2—2 of Fig. 1.

Fig. 3 is a staggered vertical sectional view taken on line 3—3 of Fig. 2.

Fig. 4 is a sectional view taken on line 4—4 of Fig. 2; and

25 Fig. 5 is a horizontal sectional view taken on line 5—5 of Fig. 3.

Similar reference characters refer to similar parts in the several views of the drawings.

As conducive to a clearer understanding of certain features of the device of the present invention, it might here be pointed out that in establishments having coin operated machines, there is a constant demand for coins of proper denomination, and more particularly nickels, by the persons playing these machines. As a rule, some person in the establishment, in addition to waiting on customers and other duties, is charged with the responsibility of making change to supply the players with nickels. Generally, the nickels are kept in a bag or other container and the person making change must count out the nickels during each change transaction, which is a burdensome and time-consuming operation. Furthermore, it will be appreciated that, as a general rule, the demands for change rise sharply as the number of patrons in an establishment increases. Thus, as play of the coin machines increases, the person charged with making change must devote more time to these transactions,

40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

55 imum.

Referring now to the drawing, the mechanism of the machine is enclosed by a housing generally indicated at 10, which includes a top 11 (Fig. 1), a front wall 12, a rear wall 13, side walls 14 and 15, and a bottom or base 16. The front, back and side walls 12, 13, 14 and 15 are detachably secured to base 16 by means of screws or other suitable fastening means 17, thus permitting the housing to be removed from the base 16, for purposes of inspection or repair of the mechanism normally enclosed by the housing.

The mechanism of the machine is mounted on the base 16 (Figs. 2 and 4) by means of a framework which includes three vertical supports 18, 19 and 20, and a platform 21, the vertical supports being secured to the base and to the platform in any suitable manner as by screws, or other fastening means. It will be noted that the platform (Fig. 2) is inclined at an angle of approximately 30° with respect to the horizontal. A hopper, indicated generally by numeral 24, is mounted on the platform 21, and includes a circular shaped base 23 (Fig. 3), secured to the platform. The inner wall of the hopper is formed by a sheet metal member which includes a cylindrically shaped top portion 24a (Figs. 1 and 2), having its axis vertically positioned with respect to the horizontal, and a cylindrically shaped lower portion 24b (Figs. 3 and 4), having its axis perpendicular to the plane of the platform 21. The lower edge portion of member 24a and the upper edge portion of member 24b are connected in any suitable manner such as by soldering. To reinforce portion 24b of the hopper wall a pair of cylindrically shaped sheet metal members 25 and 26 are provided. These members are arranged in telescopic relationship with respect to each other and to portion 24b of the hopper wall, and are secured to the hopper wall by means of bolts 27 (Fig. 2). It will be noted that the lower edge of portion 24b (Fig. 3) and of the reinforcing member 25 terminate adjacent the upper surface of the base 23, but that the lower edge of reinforcing member 26 extends downwardly over the edge of the base. This permits the lower portion of member 26, and thus the whole hopper, to be secured to base 23 by means of screws 28.

The bottom of the hopper is formed by a circular plate 29 secured to base 23, and a rotatable disc 30, having a plurality of circular openings 31, the diameters of which are slightly greater than the diameter of a nickel. The thickness of disc 30 is slightly greater than the thickness of a nickel, and thus each opening, when considered in combination with plate 29, forms a pocket adapted to receive a nickel. The disc 30 is provided with a hub 33 riveted to the center of the disc by rivets 34, the hub 33 extending downwardly through an opening 35 in plate 29, and into a recess 36 in base 23. A shaft 37 is connected to hub 33 in any suitable manner such as welding, and provides means through which disc 30 is driven by a motor 38.

The motor 38 (Fig. 2) is mounted on a U-shaped bracket 39 (Figs. 2 and 3) which is attached to the bottom of platform 21 by means of screws 40. The shaft 41 of motor 38 is connected to suitable gear reduction mechanism (not shown) contained within the motor housing, and the shaft of the gear reduction mechanism is connected to the shaft 37 by means of a coupling 42. The lower end of the motor shaft 41 is provided with a fan 41a, adapted to circulate air within housing 13.

When the machine is in use, the motor 38 drives disc 30, and the coins in the hopper fall into the openings 31 and are carried by the disc in a counterclockwise direction, as viewed in Fig. 3, to an opening 43 in plate 29. To prevent the coins, which are to be stacked, from jamming the opening 43, a shield or partition member 44 is provided (Figs. 3 and 4). The shield or partition member extends from the upper surface of disc 30 to the top of the hopper, and is held in position by a bracket 45 attached to the top 11 of the housing, and by having its flanged ends 44a and 44b soldered to the side wall of the hopper. The shield prevents the coins from entering the section of the hopper containing opening 43 unless they are carried to the opening when positioned in one of the openings in disc 30. It has been found that the coins are not always correctly positioned in openings 31 and to prevent such coins from jamming the mechanism, if permitted to come into contact with shield 44, a brush or deflector member 46 (Figs. 3 and 4) is mounted on the hopper wall by a bracket 47. This brush is constructed and arranged to properly position the coins so that the lowermost faces thereof engage plate 29.

The base 23 of the hopper, and the inclined platform 21 upon which the hopper is supported, are provided with oval shaped openings 47 and 48, respectively, which openings are aligned with the opening 43 of the plate 29. Attached to the underside of the platform 21 by means of brackets 49 and 50, suitably secured to the platform by screws 51 (Fig. 2), is a funnel shaped housing 52, having its outlet portion arranged in telescopic relationship with a coin stacking tube 53. It is to be particularly noted that the minor diameters of the oval shaped openings 47 and 48 are greater than the diameters of the coins to be stacked, that is to say, of greater diameter than a nickel, and accordingly, the size and shape of these openings insure that each coin delivered to the opening 43 of plate 29 will pass into the funnel 52, and thence to the stacking tube.

Referring to Figs. 3 and 5, it will be noted that the lower end of the stacking tube 53 extends through and is supported by an L-shaped bracket, generally indicated by numeral 55, which includes a vertical portion 55a and a horizontal portion 55b. The vertical portion is secured to the base 16 by means of screws 56, and the horizontal portion is attached to portion 55a by screws 57. Additional support for the horizontal portion 55b is provided by an angle bar 63, which is attached to said portion by screws 64, the angle bar being connected at its ends to the vertical framework support 19 and to a bar 65, having its end portions attached to the framework supports 18 and 20. The lower end of the stacking tube 53 extends through an opening 59 formed in portion 55b and is connected thereto by means of a bracket 60 and a clamp 61, adapted to be drawn into clamping engagement with the tube by means of a threaded bolt 61a and nut 61b.

The mechanism, used to dispense coins which have been stacked in the tube 53, indicated generally by numeral 66 (Fig. 3), is mounted on portion 55b of the support 55 and includes a U-shaped metal bracket 67, the legs of which are connected to portion 55b by suitable screws 68. This bracket forms a support and a guide for a slide 70 which is movable longitudinally of portion 55b. The slide 70 is formed with an opening 71, which is of slightly greater diameter than the diameter of a nickel, and a spring 72 is pro-

vided to bias the slide to the right, as viewed in Figure 3. Movement of the slide in the direction indicated is limited by means of a stop 13. When the slide 70 is in engagement with stop 13, opening 71 is in register with the lower end of the tube, so that the coins passing down the tube enter the opening 71, the lowermost coin engaging the bottom of the bracket 67. Preferably, the thickness of slide 70 is equal to the thickness of five stacked nickels.

To dispense coins, the operator reaches in thru opening 75 (Fig. 1) in the front of the housing 10, and by means of a fingerpiece 76 (Fig. 3) moves the slide 70 to the left against the bias of spring 72, until the end of the slide engages a stop 77. At this time the bottom of opening 71 clears the bracket 67, and the coins fall into the hand of the operator. The coins stacked in tube 53 above slide 70 are held in the tube by the top of the slide.

To automatically refill tube 53, when coins are dispensed, a pair of switches 80 and 81 are provided. These switches are in parallel with the circuit of the motor 38, and thus the motor will continue to operate until both switches are opened. The switches 80 and 81, include nose portions 80a and 81a which extend through openings 53a and 53b formed in the tube 53. When the tube is being filled with nickels, the stack of coins first act on nose portion 81a of switch 81 to open contact points 81b, and next acts on nose portion 80a of switch 80 to open contact points 80b, thereby breaking the circuit to motor 38 so that no more coins are fed into tube 53 by disc 30. It will be noted that the nose portion 80a is positioned above nose portion 81a, and accordingly, both switches to the motor are open, only when the tube is filled with coins. In other words, by means of the staggered arrangement of the switches, intermittent breaking of the motor circuit, by a single coin passing the nose portions in succession, is thereby prevented. The above described positioning of the switches thus provides for smooth continuous operation of the motor during the time the coins are being stacked.

The front of the machine is provided with a signal light 90 (Fig. 1), operatively connected in the motor circuit, adapted to indicate when motor 38 is in operation, which in turn indicates either that coins are being dispensed or that the hopper is empty. If the light stays on for an extended period of time, the attendant is thereby warned that the hopper is empty and should be refilled. A switch 91 is provided on housing 10 to control the supply of current to the machine.

In operation, the attendant fills the hopper 24 with coins which are fed from the hopper to tube 53 by the disc 30. The inclination of the bottom of the hopper is such as to cause the coins to slide downwardly against the wall of the hopper and in a position to seat in the openings formed in the rotatable disc, and thence fed to the stacking tube. When the tube 53 becomes filled with coins the motor 38 stops. The attendant then may dispense coins into the palm of his hand, by means of the slide 70, receiving five nickels each time he actuates the slide. As soon as coins are removed from the tube, the motor again starts and refills tube 53.

With reference to the inclination of the bottom of the hopper, it has been found, after considerable research and experimentation, that the most efficient distribution of the coins within

the hopper, that is to say, desired movement of the coins to seated positions in the openings of the rotatable disc, is obtained when the bottom of the hopper is inclined at an angle of approximately 30° with respect to the horizontal. At this particular angle, namely, 30° or substantially 30°, the coins slide downwardly, under the influence of gravity, and collect in a comparatively loose, well distributed pile or stack against the wall of the hopper. As the disc rotates, the coins at the bottom of the pile move along in the direction of rotation of the disc, and those which do not become seated in the openings therein, tumble back into the pile.

If the slope of the hopper is greater than substantially 30°, the coins tend to stack in a rather compact mass along the side of the hopper, and if the slope is less than approximately 30° the coins fail to accumulate in the required position to be transferred by the disc to the discharge opening which leads to the stacking tube. As above indicated, at an angle of approximately 30°, the coins fed to the hopper readily seat in the openings in the disc, when the disc is rotated, and the stacking tube becomes filled with coins in minimum time.

While the machine has been described as electrically driven, it is to be understood that the present invention comprehends the use of other driven means, for example, a hand driven arrangement for rotating the coin distributing disc may be used.

What I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claims.

I claim:

1. In a coin dispensing machine, in combination, a hopper, a dispensing tube positioned below the hopper, a rotatable disc mounted on the bottom of said hopper, said disc having openings therein slightly larger than the diameter of the coins being dispensed, the openings in the disc feeding coins to the upper end of said tube, an electric motor for driving the disc, a pair of switches mounted on said tube, each of said switches including nose portions extending into the tube, said nose portions being vertically spaced, with respect to each other, the switches being connected in parallel in the motor circuit, whereby the circuit to said motor is broken when both switches are open, the coins in said tube acting successively upon the nose portions of the switches to move the same to open positions when coins stacked in said tube reach the level of each nose portion, and means for dispensing coins from the lower end of the tube.

2. In a coin dispensing machine, in combination, a hopper including a base, the base of said hopper being inclined at an angle of approximately 30° with respect to the horizontal, a rotatable disc mounted on the bottom of said hopper, said disc having a plurality of openings therein equispaced from the axis of rotation of the disc, a dispensing tube extending downwardly from the hopper and having a mouth portion beneath said rotatable disc, said openings passing over said mouth when the disc is rotated, an electric motor for driving said disc, a pair of switches mounted on said tube and connected in parallel

in the motor circuit, the circuit to said motor being broken when both of the switches are in open position, said switches including nose portions extending into the dispensing tube, said nose portions being vertically spaced with respect at each other, whereby the coins in said tube open said switches successively when the stacked coins in said tube reach the level of each nose portion, means for preventing coins other than the coins seated in said openings in the disc from being fed to the mouth of said tube, brush means for properly positioning the coins in said openings, and means for dispensing coins in measured quantities from the lower end of the dispensing tube.
